UNITED STATES PATENT OFFICE

2,675,988

FEELER ACTUATED VALVE

Irwin L. Fife, Oklahoma City, Okla.

Application April 27, 1950, Serial No. 158,563

1 Claim. (Cl. 251—284)

1

The invention relates to valves for controlling the flow of fluid to or through a conduit or pipe line, and more particularly, it relates to controlling the flow of air to the intake line of vacuum controlled apparatus.

Although the valve of the present invention might well be put to other uses, it is primarily designed to be used in connection with a feeler arm which is moved to a plurality of positions by some other mechanical force.

The valve of the present invention, together with its feeler arm, is designed particularly for use in connection with web guiding apparatus for laterally shifting a roll of sheet material as it is unwound therefrom, or as it is being wound thereon.

In the present day art of guiding travelling webs, it is conventional practice to utilize vacuum controlled power operated mechanism for shifting a web carrying roll, so that an edge of the web will be properly aligned with a web receiving apparatus, usually consisting of another roll. It has heretofore been found practical to utilize electrical power for laterally shifting the web carrying roll, and to control the application of such power by vacuum pressure. In such web guiding apparatus, one or both edges of the travelling web or sheet is or are used for controlling the lateral direction in which the web carrying roll is shifted.

The words "vacuum pressure," as used herein, are intended to mean any pressure which is below the current and normal atmospheric pressure.

Some conventional web guiding mechanisms pass the edge of the web flatly over an orifice plate or plates through which air must travel to reach a vacuum creating device. In such mechanisms, variation in the lateral position of the web edge acts to control the direction of roll shift, and no valve is used on the intake line of the vacuum producing equipment. In this case, the web edge acts as a valve for controlling the ingress of air.

In handling some types of sheet material, for instance porous or woven materials, orifice plates cannot successfully be used because of the fact that air will pass through the material. It therefore becomes necessary to use feeler actuated valves for controlling ingress of air to the intakes of the vacuum producing devices. The present feeler actuated valve is particularly designed for such a use.

It is therefore the principal object of the present invention, to provide an extremely sensitive feeler actuated valve for controlling the ingress

2

of air to vacuum pressure producing equipment.

Another object of the present invention, is to provide a valve of this class which is positive in action, and which will properly function over long periods of time.

It is pointed out that when once placed in service, a valve for this purpose is almost constantly in motion, and therefore to be practical, it must be so designed that there is little or no wear on its moving parts. It is further pointed out that, in order for such a valve to be actuated by the contact of the edge of all types of soft or flimsy sheet materials, it must be highly sensitive and easily operated. The valve of the present invention has been designed with these purposes in mind.

Other objects will be apparent from the following description when taken in conjunction with the accompanying two sheets of drawings,

20 wherein:

Figure 1 is a perspective view of the valve and feeler arm;

Figure 2 is a perspective view looking at the other end of the valve;

25 Figure 3 is a vertical sectional view taken substantially along the line 3—3 of Fig. 2;

Figure 4 is an exploded perspective view illustrating the elements which go to make up the general valve assembly; and,

30 Figure 5 is a similar view illustrating the parts which go to make up the valve core assembly.

Like characters of reference designate like parts in those figures of the drawings in which they occur.

35 In the drawings:

The reference numeral 1 indicates, as a whole, a tubate cylindrical valve housing having both ends open, and having an internally threaded inlet opening or perforation 3 through its annular 40 wall. The perforation 3 is adapted to receive the threaded end of a pipe fitting 4 through which air must travel in reaching the interior bore 5 of the housing.

45 Pressed into the bore of the housing 1, and rigidly disposed therein adjacent one end, is an annular metal ring 6. Adjacent the outer edge of the ring 6, the bore 5 is provided with an annular groove 7 which is machined therein. An annular closure plate 8 having an axial threaded bore 9 is adapted to be inserted into the end of the housing 1, and to seat against the outer end of the ring 6. A conventional split ring 10 of spring metal is adapted to be compressed and snapped into the groove 7 so as to hold the closure plate 8 in seated position against the ring 6.

The reference character A indicates, as a whole, a valve core assembly which is adapted to be inserted into the housing 1, from the other end, and which includes a tubate sleeve 11.

The outer surface of the sleeve 11 is provided with an elongated arcuate cavity 12 having abrupt end walls 13 and 14, and an elongated through slot 15 is located in the bottom of the cavity 12 and is co-extensive therewith.

The sleeve 11 is further provided with an elongated arcuate through slot 16 having abrupt end walls 17 and 18. The slot 16 lies parallel to the two end edges of the sleeve 11, and follows the periphery of the sleeve for approximately 120 degrees of its circumference.

As best illustrated in Fig. 5, the valve core assembly further includes a rotor or closure block 19 having its side edges 20 and 21 arcuated to form a working fit with the inside wall surface of the sleeve 11, when the block is inserted into the bore of the sleeve. The block 19 is centrally bored longitudinally to receive, and is rigidly mounted upon, a shaft 22, which projects beyond each end of the block. A conventional frictionless bearing 23 is provided around the shaft 22 at each end of the block 19. The side edge 21 of the block 19 has a threaded bore 24 adapted to receive one end of a stud 25.

The first step in assembling the core assembly A, is to insert the block 19 and its shaft 22 into the sleeve 11, so that the arcuate side edge 20 of the block is disposed adjacent the inner opening of the slot 15 through the sleeve. The threaded stud 25 is then inserted through the arcuate slot 16 and into the threaded bore 24, and is rigidly screwed into the bore 24. It is obvious that when so installed in the sleeve 11, rotative motion of the block is limited by the distance to which the stud 25 can travel in the slot 16 before being stopped by one of its end walls 17 or 18.

The core assembly A further includes a bearing or closure disc 26 having a central through bore 27 for surrounding the shaft 22, and having a plurality of through perforations 28 for permitting passage of air therethrough. The inner face of the disc 26 has a cylindrical cavity for nesting the left hand bearing 23.

Surrounding the left hand end portion of the shaft 22 and lying against the outer left hand face of the disc 26 (as viewed in Fig. 5), there is provided a helical spring 29 having its inner looped end 30 anchored to the shaft in any suitable or conventional manner, for instance by a pin, not shown, inserted into a perforation 35 in the shaft. The other looped end 32 of the spring 29 is anchored to the disc 26 by either of two pins 31 or 33. A cover plate 34 is placed around the left hand end portion of the shaft 22, and lies against the outer left hand edge of the spring 29. Any suitable detent, not shown, may be used to retain the plate 34 against longitudinal movement along the shaft.

The other or right hand end of the sleeve 11 is adapted to be closed by a disc 36 having a cylindrical cavity 37 for nesting the right hand frictionless bearing 23. In assembly, the disc 36 is pressed into the sleeve 11 so as to remain anchored thereto.

As best shown in Fig. 4, the right hand protruding end portion of the shaft 22 is equipped with a transversely extending feeler arm 38. The feeler arm 38 is preferably composed of a sleeve portion 39 adapted to surround the shaft, a set-screw 40 for retaining the sleeve portion 39 on the shaft 22, and an elongated blade portion 41

rigidly carried by the sleeve portion 39. When the core assembly is thus assembled, it is thrust into the bore of the valve housing 1 through the open right hand end thereof. When so positioned in the housing 1, the left hand end of the sleeve 11 rests against the right hand end of the ring 6, and the extreme left hand portion of the shaft 22 terminates short of the inner end of the central bore 9 of the closure plate 8.

As best illustrated in Fig. 3, the arcuate slot in the sleeve 11 is so positioned that when the stud 25 is in contact with the end wall 17, the inlet slot 15 is barely closed, and the least counter clock-wise movement of the block or core 19, as viewed in Fig. 3, will partially open the slot. Very little further counter clock-wise movement of the core 19 will fully open the slot 15. It is pointed out that since the slot 15 is elongated, and the core 19 is of greater length and moves across it, very little lateral swinging movement of the core across the slot is necessary to admit a considerable amount of air through the slot. It is further pointed out that since the core is in a shearing position with relation to the slot 15, and since the core is symmetrical and sensitively balanced, very little moving power need be applied to the arm 38 to open or close the slot 15.

It will be noted that the housing 1 is eccentrically bored. While this feature is preferable in order to obtain a thicker wall at the inlet opening 3, it is not mandatory.

In operation, the valve housing with its associated and assembled parts is rigidly mounted adjacent one edge of the traveling web or sheet, in such a position that the arm 38 lies just outside of the desired path of such sheet edge. The sheet is indicated by the reference numeral 45 (Fig. 3). The intake pipe of a vacuum pump, not shown, is connected to the threaded bore 9 of the closure plate 8 by a suitable fitting 44 (Fig. 1). When the housing is so mounted, the spring 29 acts to hold the core 19 in a radial position to close the slot 15 against the entry of air therethrough. Should the traveling sheet edge thereafter shift toward the arm 38, as illustrated in solid lines in Fig. 3, the arm 38 will be swung laterally to the solid line position of Fig. 3, and the core 19 will be moved in a left hand direction to partially open the orifice slot 15, as also shown in solid lines in said Fig. 3. Further right hand motion of the edge of the sheet 45 will act to fully open the orifice slot 15, as illustrated in dotted lines in Fig. 3.

It will be understood, that a mechanical roll shifting apparatus, not shown, will be actuated to move the roll of sheet material or web in a left hand direction, as soon as air is permitted to pass through the slot 15. Such left hand movement of the web carrying or guiding roll will similarly shift the edge of the sheet 45 in a left hand direction (Fig. 3), which will permit the core 19 to return to its slot closing position.

One of the valve assemblies of the present invention, if found desirable, may be installed adjacent each side edge of the sheet 45.

Obviously the invention is susceptible to some change or alteration without defeating its practicability, and I therefore do not wish to be confined to the preferred embodiment shown in the drawings and described herein, further than I am limited by the scope of the appended claim.

I claim:

In a valve, the combination with a hollow cylindrical housing having a lateral inlet, and having

an outlet in one end, of a valve core assembly within said housing, said assembly including: a tubular sleeve within the housing and having an exterior concavity coinciding with the inner end of said inlet; an elongated through slot in the wall of said sleeve and communicating with said concavity; a rock-shaft journalled for partial rotation in said sleeve; a closure block coactive with the shaft and adapted to move transversely across said slot to open and close the same; means for limiting the rocking movement of the shaft and block; a spring urging the shaft in one rotative direction; and means for closing the two ends of the housing.
